(57) **CLAIM**

The ornamental design for a pet training kit as shown and described.

DESCRIPTION

FIG. 1 is a perspective view of a pet training kit, showing my new design;

FIG. 2 is a perspective view of a first transmitter of the pet training kit, shown separately for ease of illustration;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof.

FIG. 10 is a perspective view of a second transmitter of the pet training kit, shown separately for ease of illustration;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a perspective view of a receiver of the pet training kit, shown separately for ease of illustration;

FIG. 19 is another perspective view thereof;

FIG. 20 is a front elevational view thereof;

FIG. 21 is a rear elevational view thereof;

FIG. 22 is a left side elevational view thereof;

FIG. 23 is a right side elevational view thereof;

FIG. 24 is a top plan view thereof; and,

FIG. 25 is a bottom plan view thereof.

The broken lines in the drawings depict portions of the pet training kit that form no part of the claimed design.

1 Claim, 25 Drawing Sheets
